SEWING MACHINE

Matthew G. Ivandick, Rockford, Ill., assignor to
Free Sewing Machine Co., Rockford, Ill., a cor-
poration of Illinois

Application March 24, 1944, Serial No. 527,864

21 Claims. (Cl. 112—258)

1

This invention relates to an improved sewing machine, the head of which is adapted to be tilted about an axis at right angles to the longitudinal center line of the head, to facilitate the removal and replacement of the bobbin.

The bobbin requires refilling at least five times per spool of thread, and in the conventional sewing machine the bobbin is not at all easily accessible and can be reached usually only through a small opening in the bedplate when a slideable closure is moved out of the way. It is therefore the principal object of my invention to provide a head tiltable with the bedplate about a transverse axis located intermediate the ends of the head at a point where the head is substantially balanced with respect to the tilting axis, whereby a woman will have no difficulty in manipulating the same when the bobbin has to be removed.

Another important object of my invention is to provide a sewing machine in which the head has supporting means permitting tilting of the head with the bedplate about one longitudinal edge portion of the plate in the conventional manner, the bedplate being, however, detachably connected with one of the two hinge members forming said supporting means, whereby to permit tilting of the head about the transverse axis on which the other hinge member is located.

The invention is illustrated in the accompanying drawings in which—

Fig. 1 is a plan view of a sewing machine embodying my invention, certain portions being broken away and indicated in section to better illustrate the various novel features;

Fig. 2 is a front view illustrating the head tilted about the transverse axis;

Fig. 3 is an end view illustrating the head tilted in the conventional manner;

Figs. 4 and 5 are cross-sections on a larger scale taken on the correspondingly numbered lines of Fig. 1;

Fig. 6 is a longitudinal section on the same scale as Figs. 4 and 5, taken on the line 6—6 of Fig. 1, and

Fig. 7 is a longitudinal section on the line 7—7 of Fig. 1.

The same reference numerals are applied to corresponding parts throughout these views.

The reference numeral 10 designates a portion of the sewing machine cabinet, the top of which provides the usual working surface that is usually substantially flush with the bed- or cloth-plate 11 of the machine. The head is indicated generally by the reference numeral 12 and is rigid with the bedplate and comprises the usual overhang-

ing arm or standard 13, terminating in the head portion 14 in which the needle bar 15 and presser foot 16 operate. A generally rectangular opening 17 is provided in the working top portion of the cabinet 10, in which the bedplate 11 fits with ample clearance so as to permit tilting of the head about the axis AB as in Fig. 3 or about the transverse axis CD as in Fig. 2. Tilting about the axis AB is common in this art and permits easily oiling the mechanism under the bedplate. Tilting about the transverse axis CD facilitates removal and replacement of the bobbin and in accordance with my invention, this axis is at right angles to the longitudinal center line of the head and is located adjacent the inner side of the base portion of the standard so that the head is substantially balanced with respect to this axis and a woman operator will have no difficulty whatsoever in manipulating the head in this way. The importance of ease of operation in tilting about the transverse axis CD can be appreciated when it is realized that the bobbin has to be removed for filling at least five times per spool of thread placed on the spindle 18.

Two hinges 19 and 20 have pintles 21 and 22 which are located on the axis AB and pivotally connect the fixed hinge members 23 and 24 with the swingable hinge members 25 and 26. The bedplate 11 has a bearing boss 27 cast integral with the bottom thereof to receive a trunnion 28 provided on the hinge member 26. A screw 29 threaded in the boss 27 projects into an annular groove 30 in the trunnion 28 to provide a more or less permanent but detachable connection with the hinge member 26. A similar trunnion 31 is provided on the hinge member 25 which, however, has an enlarged head portion 32 on the inner end thereof, and the bedplate 11 has a forked boss 33 cast integral with the bottom thereof and adapted to fit over this trunnion behind the head portion thereof for a quickly detachable connection with the hinge member 25. A latch pin 34 is slidable in registering holes 35 provided in the two halves of the forked boss 33 as indicated in Fig. 6, to lock the bedplate onto the trunnion 31 until such time as it may be desired to tilt the head about the transverse axis CD. A lug 36 is cast integral with the bottom of the bedplate in longitudinally spaced relation to the boss 33, and has a hole 37 therein in coaxial relation to the holes 35 to provide a guide and support for the latch pin 34 as well as an abutment for a coiled compression spring 38, which is assembled on the pin in front of the lug 36 and engages a collar 39 fixed by means of a

set screw 40 to the pin, whereby the pin is normally urged in one direction toward locked position. A knob 41 is slideable in a slot 42 provided in the bedplate and is threaded on the upturned end 43 of the latch pin to permit manual operation of the latch pin to unlock the bedplate from the trunnion 31 when the head is to be tilted about the transverse axis CD. The hinge members 25 and 26 are forked to provide a space in each of these members for the coiled portion of a grasshopper-type spring 60, one leg of which enters a socket in the fixed hinge member and the other leg of which enters a socket in the swingable hinge member, the coiled portion being supported on the hinge pintle. These springs resist swinging movement of the hinge members 25 and 26 and normally hold said members in the horizontal position shown in Figs. 4 and 5 so that there will be no difficulty in reconnecting the bedplate 11 with the trunnion 31 after it has been disconnected for tilting of the head about the transverse axis CD.

The bedplate is supported opposite the trunnions 28 and 31 on pin projections 44 and 45 coaxially aligned with said trunnions. The pin 45 does not require such coaxial alignment, but the pin 44 must be so aligned with the trunnion 28 to permit tilting of the head about the axis CD. The pin 44 is on a plate 46 fastened as by means of screws 47 to the cabinet in the opening 17, and this pin fits in a forked boss 48 cast integral with the edge portion of the bedplate. The other pin 45 is also carried on a plate 49 fastened to the cabinet 10 by screws 50 in the opening 17, and this pin fits in a forked boss 51 cast integral with the edge portion of the bedplate. A spring-pressed, bullet-type detent 52 is provided in the boss 48 and is adapted to ride into either one of two holes 53 and 54 provided therefor in the plate 46 to lock the bedplate releasably in its normal position represented in Figs. 1 and 4, at which time the detent engages in the hole 53, or in the tilted position of Fig. 2, at which time the detent enters the hole 54. A thumb piece 55 is provided on the detent 52 operable in a small slot 56 provided therefor in the bedplate 11, as shown in Fig. 4, whereby to permit easy withdrawal of the detent from either of the holes 53 and 54. The holes 53 and 54 are located on an arc struck with the axis CD as a center, so that the detent 52 which is spaced a predetermined radial distance with respect to the pin 44, as clearly appears in Fig. 1, will come into register with the hole 54 when the head is tilted from its normal position to that shown in Fig. 2, and will snap into place with an audible click so that the operator will know definitely when the head is locked and can proceed accordingly with the removal of the bobbin, with assurance that the head will not be apt to drop accidentally.

In operation, the head is normally supported as shown in Figs. 1, 4, 5, 6 and 7. When it is desired to tilt the head on the axis AB the detent 52 is withdrawn from the hole 53 by operation of the thumb piece 55, and the head can then be raised and swung rearwardly, as shown in Fig. 3, thereby exposing the mechanism under the bedplate for easy cleaning and oiling. Then when the head is swung back again, the detent 52 is retracted manually to permit lowering the bedplate to its normal position substantially flush with the working top surface of the cabinet 10, and the detent will snap into place in the hole 53 with an audible click, indicating that the head is properly locked and the machine is ready for use. When it is de-

sired to remove the bobbin for refilling, the knob 41 is moved to the right so as to retract the latch pin 34 in relation to the trunnion 31, whereupon the head can be tilted about the transverse axis CD. In this operation, due to the location of the axis, it requires much less effort to tilt the head than in tilting about the axis AB, and it is due to the balanced condition of the head in this tilting that very light detent action is sufficient to lock the head fairly securely in the tilted position shown in Fig. 2. The detent 52 snaps into place in the hole 54 when the head reaches the degree of tilt indicated, and there is an audible click to indicate to the operator when the head has been locked, and it is safe to release the hold on it and proceed with the operation of removing the bobbin. Obviously with the head tilted as shown in Fig. 2, the bobbin is amply exposed and easily accessible. I prefer to have the end of the detent 52 rounded to a spherical form and to have the hole 53 slightly smaller in diameter than the hole 54, with a view to permitting the detent to ride only slightly into the hole 53 so that there is no need for manipulating the thumb piece 55 when raising the head in tilting about the axis AB or in raising the head in tilting about the axis CD, whereas the detent 52 will enter the hole 54 far enough to provide a secure hold and one which will require manipulation of the thumb piece 55 to release it. In that way any danger of accidental dropping of the head is definitely eliminated.

It is believed the foregoing description conveys a good understanding of the objects and advantages of my invention. The appended claims have been drawn with a view to covering all legitimate modifications and adaptations.

I claim:

1. In a sewing machine, the combination with a support, of a substantially rectangular bedplate rigidly supporting a sewing machine head, and two-way hinge means hingedly connecting said bedplate to said support providing portions adapted to pivot on two axes that are in transverse relation and both substantially in the horizontal plane of said bedplate, whereby said plate is adapted to be tilted about a longitudinal axis relative to said support or the plate may be tilted about a transverse axis relative to said support.

2. In a sewing machine, the combination with a support, of a substantially rectangular bedplate rigidly supporting a sewing machine head, and two-way hinge means hingedly supporting said bedplate on said support providing portions adapted to pivot on two axes that are in transverse relation and both substantially in the horizontal plane of said bedplate, for tilting of the plate relative to said support about a longitudinal axis substantially parallel with one longitudinal edge portion of said plate and for tilting of said plate relative to said support about a transverse axis.

3. In a sewing machine, the combination with a support, of a substantially rectangular bedplate rigidly supporting a sewing machine head, and two-way hinge means hingedly supporting said bedplate on said support providing portions adapted to pivot on two axes that are in transverse relation and both substantially in the horizontal plane of said bedplate, for tilting of the plate relative to said support about a longitudinal axis substantially parallel with one longitudinal edge portion of said plate and for tilting of said plate relative to said support about a transverse axis located intermediate the ends of said

plate at a point where the weight of the tiltable mass is substantially balanced with respect to said transverse axis.

4. In a sewing machine, the combination with a support, of a substantially rectangular bedplate carrying a sewing machine head, a pair of hinges on said support in longitudinally spaced relation with respect to one longitudinal edge portion of said plate for support thereof for tilting on a longitudinal axis substantially parallel to said edge portion, a plate supporting projection on said support under the opposite longitudinal edge portion of said plate disposed on a line substantially normal to the aforesaid axis and passing through one of said hinges for support of said plate for tilting on a transverse axis coincident with said line, means connecting said plate with the last mentioned hinge for pivotal movement of said plate relative to said hinge on said transverse axis, and means detachably connecting said plate to the other hinge.

5. A sewing machine as set forth in Claim 4 wherein said plate supporting projection and the related hinge are located intermediate the ends of said plate so that the weight of the tiltable mass represented by the plate and head is substantially balanced with respect to said transverse axis.

6. In a sewing machine the combination with a support, of a substantially rectangular bedplate carrying a sewing machine head, a pair of hinges comprising fixed hinge members attached to said support in longitudinally spaced relation with respect to one longitudinal edge portion of said plate and swingable hinge members pivotally connected to the fixed hinge members by pintles on an axis substantially parallel to the adjacent longitudinal edge portion of said plate, a trunnion on one of said swingable hinge members substantially at right angles to the hinge pintle having said edge portion of said plate pivotally supported thereon, a substantially horizontal pin projection on said support adjacent the opposite side of said plate and coaxially aligned with the trunnion in its horizontal position, said plate being adapted to tilt with respect to said pin and trunnion on a transverse axis, and means detachably connecting said plate to the other swingable hinge member.

7. A sewing machine as set forth in claim 6 wherein said pin projection and trunnion are located on a line coincident with the transverse axis intermediate the ends of said plate so that the weight of the tiltable mass represented by the plate and head is substantially balanced with respect to said transverse axis.

8. A sewing machine as set forth in claim 6 including means associated with at least the last named swingable hinge member for supporting the same in a predetermined position projecting from the support when not attached to the plate, for the purpose described.

9. A sewing machine as set forth in claim 6 including spring means associated with at least the last named swingable hinge member for supporting the same in a predetermined position projecting from the support when not attached to the plate, for the purpose described.

10. In a sewing machine, the combination with a support, of a substantially rectangular bedplate carrying a sewing machine head, means hingedly connecting said bedplate to said support whereby said plate is adapted to be tilted about a longitudinal axis relative to said support and also tilted about a transverse axis relative to said support, and a single detent means for selectively releas-

ably locking said plate in normal position and tilted position.

11. In a sewing machine, the combination with a support, of a substantially rectangular bedplate carrying a sewing machine head, and means hingedly supporting said bedplate on said support for tilting of the head with the plate relative to said support about a longitudinal axis substantially parallel with one longitudinal edge portion of said plate and for tilting of said head with the plate relative to said support about a transverse axis, and a detent device on the free longitudinal edge portion of said plate for cooperation with a keeper plate on said support for selectively releasably locking said plate in working position and in a moved inoperative position tilted on the transverse axis.

12. A sewing machine as set forth in claim 11 wherein said detent device and keeper plate are so constructed and arranged whereby to provide an easily releasable hold for the plate in working position and a relatively positive locking action in tilted position, said detent device including a manually operable member for releasing the same from the locking position.

13. A sewing machine as set forth in claim 11 wherein said detent device comprises a spring-pressed plunger having a rounded outer end, and the keeper plate has holes provided therein of different sizes for different depths of engagement of the plunger therein in different positions of the plate, whereby to releasably secure the plate in working position so that light pressure on the head releases the plate, and whereby to relatively positively lock the plate in tilted position, requiring heavy pressure on the head to release the same.

14. A sewing machine as set forth in claim 11 wherein said detent device comprises a spring-pressed plunger having a rounded outer end, and the keeper plate has holes provided therein of different sizes for different depths of engagement of the plunger therein in different positions of the plate, whereby to releasably secure the plate in working position so that light pressure on the head releases the plate, and whereby to relatively positively lock the plate in tilted position, requiring heavy pressure on the head to release the same, said detent device including a manually operable member for retracting the plunger.

15. In a sewing machine, the combination with a support, of a substantially rectangular bedplate carrying a sewing machine head, and means hingedly supporting said bedplate on said support for tilting of the head with the plate relative to said support about a longitudinal axis substantially parallel with one longitudinal edge portion of said plate and for tilting of said head with the plate relative to said support about a transverse axis located intermediate the ends of said plate at a point where the weight of the tiltable mass is substantially balanced with respect to said transverse axis, and a single detent means for selectively releasably locking said plate in working position and in a moved inoperative position tilted on the transverse axis.

16. In a sewing machine, the combination of a support, a bed-plate adapted to be supported thereon for tilting selectively in either of two directions on two axes substantially at right angles to one another, two hinges for hingedly supporting said bed-plate on said support, one of said hinges being constructed to provide a two-way pivotal connection between said bed-plate and said support permitting tilting of said bed-

plate selectively about either axis, the other hinge being constructed to permit tilting of said bedplate only about one of said axes, and means for detachably securing said bedplate to said support through the medium of the latter hinge.

17. In a sewing machine, the combination of a support, a bed-plate adapted to be supported thereon for tilting selectively in either of two directions on two axes substantially at right angles to one another, and pivot means providing three-point pivotal support for said bed-plate on said support, two of which pivots are on one of said axes and the other pivot on the other axis with one of the first two pivots, the latter pivot being constructed to permit two-way pivotal movement of the bed-plate relative to said support.

18. In a sewing machine, the combination, with a support, of a substantially rectangular bedplate carrying a sewing machine head, and means hingedly connecting said bedplate to said support for two-way tilting about a longitudinal axis relative to said support or about a transverse axis relative to said support, the transverse axis being located intermediate the ends of said plate at a point where the weight of the tiltable mass is substantially balanced with respect thereto;

19. In a sewing machine, the combination with a support, of a substantially rectangular bedplate carrying a sewing machine head, and means hingedly connecting said bedplate to said support for two-way tilting about a longitudinal axis relative to said support or about a transverse axis relative to said support, one of said axes being so located with respect to said plate where the weight of the tiltable mass is substantially balanced with respect thereto.

20. In a sewing machine, the combination, with a support, of a substantially rectangular

bedplate carrying a sewing machine head, two separate and independent hinge means tiltably supporting said bedplate for tilting movement selectively about either of two transverse axes relative to said support, and means for detachably locking said bedplate to one of said hinge means precluding tilting of the bedplate about the axis defined by the other hinge means.

21. In a sewing machine, the combination with a support of a substantially rectangular bedplate rigidly supporting a sewing machine head, and two-way hinge means for hingedly supporting said plate on said support, one portion of which means has its axis of operation parallel to one longitudinal edge portion of said plate and another portion of which means has its axis of operation parallel to one end of said plate, whereby said plate is adapted to be tilted relative to said support either about a longitudinal axis substantially parallel with the one longitudinal edge portion of said plate, or about a transverse axis substantially parallel with one end of said plate.
